PNEUMATIC IRONING AND PEENING TOOL
Albert Anders, 2106 S. Court St., Visalia, Calif., assignor
of twenty-five percent to Thelma May Gordon, North
Long Beach, Calif.

Filed Feb. 23, 1962, Ser. No. 175,161
2 Claims. (Cl. 81—15)

The present invention relates to a pneumatic ironing and peening tool for metal work. The invention contemplates a tool which may be held in the palm of the hand and which may be manipulated so as to iron or peen metal in what may generally be considered as an inaccessible location. As an example, I may mention the metal wing of an airplane. If a section such as a panel of the metal wing should become damaged, it is generally required that the damaged section be entirely removed from the wing structure in order to repair the same. With the present invention, it is generally possible to remove an inspection window in the wing structure and place the arm therein, the hand carrying the tool of the present invention and to repair the damaged area without the necessity of removing the panel. In speaking of damaged areas, I have reference to structures which have been damaged by falling objects or by the airplane wing striking some object which damages the wing covering.

The device of the invention, by being compact, may be used where the ordinary peening tool or metal shaping and ironing tool cannot be used.

An object of the invention is to provide a compact ironing and peening tool which is pneumatically operated and in which the tool is so formed as to provide portions acting as an ironing and shaping tool.

A further object is the provision of an ironing and peening tool for metal work which is easily assembled or repaired, efficient in operation, which will perform work with dispatch, easily manipulated and generally superior to devices now known to the inventor.

With the above mentioned and other objects in view, including simplicity of structure, inexpensiveness in cost of manufacture, and general efficiency, the invention consists in the novel and useful provision, formation, construction, association, and relative arrangement of parts, members and features, all as shown in one embodiment in the accompanying drawing, described generally, and more particularly pointed out in the claims.

In the drawing:

FIGURE 1 is a fragmentary, partially sectional front elevation of the device of the invention;

FIGURE 2 is a fragmentary sectional view on the line 2—2 of FIGURE 1, and showing the device of the invention engaging work;

FIGURE 3 is a fragmentary, sectional view similar to that of FIGURE 2, certain of the parts being in moved relationship from that of FIGURE 2;

FIGURE 4 is a fragmentary, sectional view on the line 4—4 of FIGURE 2; and

FIGURE 5 is a fragmentary, sectional view, on an enlarged scale, and illustrative of the spacing between certain elements of the invention.

The invention includes a substantially cylindrical member 1 having a closed end 2 of convex form to provide a shaping or ironing head, the opposite end of the casing being open. In this particular, the interior of the housing or casing from the open end is provided with a series of spaced annularly arranged eccentric bores designated generally as 3, the bores terminating inward of the head 2 and likewise provided with an enlarged axial bore 4 having one end terminating inward from the head 2 and functioning as a cylinder. The casing or housing is provided with a concentric annular groove 5 which extends inwardly from the open end of the casing or housing and

2

transversely cuts the eccentric series of bores 3, see FIGURE 4. By this construction the wall 6 bounding the cylinder 4 is of lesser depth than the outer cylindrical wall 7 of the casing or housing. The open end of the casing or housing receives a cap 8 the inner wall of the cap having two stepped annular portions 9 and 10, the portion 10 adapted to be received within the confines of the annular groove 5 while the portion 9, provided with a washer 11, abuts the end of the wall 7 of the casing or housing. Screws 12 are countersunk in the cap and received in threaded bores in the casing or housing for holding the cap and housing in working relationship as shown in FIGURES 2 and 4.

Within the cylinder 4 is a piston 13. The head 14 of the piston is provided with a circular recess 15 and the end 16 of the piston is provided with an axial bore 17 thus providing a piston skirting 17a.

A peening tool or hammer 18 is received within the bore 17 of the piston. The peening tool includes an elongated cylindrical member provided with a frusto conical end 19 and having longitudinally diametrically arranged flat sides 20 and 21. The shaping and ironing head 2 is formed with a central bore 22 which receives the peening tool or hammer and the cylinder head is centrally provided with an annular flange 23 the bore of which is the same diameter as the bore 22 and provides a further bearing surface for the peening tool or hammer. The peening tool or hammer is provided with a two flanged head, designated as 24 and 25. The flange 24 is adapted to fit within a circular groove 26 of the piston. A coil spring 27 surrounds the peening tool or hammer and extends between the flanged head and the annular flange 23 for constantly urging the peening tool inwardly of the head 2.

It is intended that the bore 22 and the bore of the annular flange 23 have flattened or broached areas for cooperation with the flattened sides 20 and 21 of the peening tool or hammer to prevent rotation thereof when the hammer is reciprocated within said bores.

The piston skirting 17a is provided with a circumferential groove 28 adapted to receive an O-ring 29. This O-ring bears against the cylinder wall. As shown in FIGURE 5 there is a slight spacing between the periphery of the piston and the cylinder wall of approximately .0025.

The peening tool or hammer 18 through the medium of the piston is pneumatically operated. Thus, referring to FIGURE 1, I have provided a valve 30 which includes a housing 31 formed with a screw threaded tapered bore 32 for connection with a threaded nipple 33, the nipple being connected to a hose 34 leading to a source of compressed air. A double screw threaded fitting 35 connects to an extension 36 of the housing 31 and likewise with the interior of the casing or housing 1, see FIGURES 2 and 4. The interior of the valve housing is chambered at 37 and within the chamber is a valve head 38. The valve head mechanism includes a stem 39 having a head 40, the arrangement being such that when the head 40 is pressed upon by the finger to move the stem 39 inwardly, the valve 41 unseats under opposing spring pressure by spring 42 and allows air under pressure directed through the hose 34 to pass through the chamber 37 and through coupling 35 into the casing or housing 1. When the valve head 38 closes, pressure air which

has moved the piston is bled through the valve housing and relieves pressure from the piston. I lay no claim to any particular valve structure for directing air under pressure into the housing 1 and the particular valve shown is illustrative only.

The operation, uses and advantages of my invention are as follows.

First, I wish to point out that the casing or housing 1

acts as a shaping or ironing tool due to the flat or plane outer surface of the cap 8, the convex surface 2 and the cylindrical wall 7. Hence, it is within the purview of my invention to turn the tool so that these surfaces may be brought against work when necessary. In FIGURES 2 and 3 I have shown the convex surface 2 in engagement with sheet metal 50 which requires reforming or shaping. Against one surface of the sheet metal I have placed a tool 51 which may be an anvil, a die, a hammer or other shaping tool. In the present instance the particular tool has a convex surface 52. When the head 40 is pressed inwardly by the finger of one hand, the same hand holding the casing or housing 1 in the palm thereof with the convex surface 2 pressed against the work 50, opening the valve 41 to admit compressed air will move the piston and direct the peening tool or hammer outwardly of the bore 19 against the work 50. In this respect it is to be observed that pressure air enters the annular groove 5 and likewise the eccentric bores 3 to accommodate a large volume of pressure air. The piston head is within a central circular recess 60 of the cap. Thus pressure air due to close tolerance of the piston head within the circular recess 60 of the cap will be directed between the cylinder wall and the periphery of the piston to enter the restricted spacing therebetween, as shown in FIGURE 5. The O-ring prevents the pressure air from passing into the cylinder ahead of the piston. Consequently, the piston will start to move slowly, and the term slow is purely relative, as the piston will move within a fraction of a second when the air pressure is four to five hundred p.s.i. to move the piston head beyond the circular recess 60 of the cap. Before this latter occurs, considerable pressure has built up within the casing or housing with the result that when the piston head is exposed, the piston is moved under considerable pressure to deliver a sudden striking blow by the hammer or peening tool 18 against the work 50. The character of the peening tool or hammer is such as to form what may be termed as a dimple in the work, as shown at 70. Quite obviously, if the end of the peening tool or hammer is relatively pointed, the character of the dimple is changed. When the finger releases the valve stem 39, air under pressure to the tool is closed and the piston retracts within the cylinder, being retracted by the spring 27. The action of the peening tool or hammer will depend, therefore, upon the rapidity with which the head 40 is actuated by the finger. By holding the convex surface 2 against the work, the deformed portion of the work can rapidly be indented or dimpled by the hammer or peening tool while the convex surface 2 shapes the work. A final smoothing of the work can be accomplished by means of any abrasive element such as by using a file. Thus to return to the shaping of a wing panel of an airplane, the tool may be inserted through an inspection window within the wing structure with the convex surface 2 bearing against the damaged area while a second shaping tool or iron may be applied to the external surface. Upon actuation of the hammer or peening tool a series of indentations or dimples are made in the work which will straighten the damaged area and restore it to its original configuration or form. Such an operation saves the removing of rivets and the complete removal of a panel of wing covering which is usually of duralumin. Thus an expensive operation is unnecessary which at best is time consuming. It will probably be realized that the average tool for shaping and ironing sheet metal is large and bulky and usually has two parts connected together by some form of bracket which does not lend ready adaptability of the tool for an ironing operation of sheet metal on the job. With my invention, the tool is manipulated by the hand and held in the palm of the

hand. The hand and arm are more sensitive in the finding of the location to be ironed than are large tools, and as a consequence, I am able to shape and iron sheet metal in various difficult zones of accessibility not possible of accomplishment with shaping and ironing tools now known to me. Easy accessibility to the working parts of the tool are afforded by removing the screws 12 to release the cap 8 from the casing or housing whereupon the cylinder and the piston may be removed and other parts inspected such as the peening tool or hammer. Re-assembly is equally easy of accomplishment.

The bores 3 in conjunction with communicating groove 5 accommodates an enlarged volume of pressure air and assures that the piston will drive the peening tool or hammer 18 against work under high pressure. Furthermore the arrangement of the bores 3 reduces tool weight while not detracting from its strength. As a result, worker fatigue is not a factor.

I claim:

1. An ironing and peening tool for sheet metal including a shaping tool capable of being carried in the hand of an operator for manually-controlled pressure against the sheet metal, including: a cylindrical casing one end of which is provided with a convex surface to act as a shaping and ironing head, said cylindrical casing provided with an axial cylinder having a closed end adjacent the convex head and an open end, the cylindrical casing formed with a circular recess concentric with the cylinder at the open end of the cylinder, a cap secured to the cylindrical casing and closing the open end of the cylinder and the circular recess, a piston within the cylinder, the piston having a head and the cap being provided with a circular recess to receive with close tolerance a portion of the piston head, the piston formed with a skirting to provide a central bore therein and facing the closed end of the cylinder, the external diameter of said skirting being less than the internal diameter of the cylinder to provide a restricted spacing therebetween, there being an external annular groove on said skirting and an O-ring positioned in the annular groove for contact with the cylinder, the shaping and ironing head of the cylindrical casing provided with a central bore, a peening hammer slidably confined in part within said central bore and the central bore of the piston and spring pressed against the piston head, means for admitting fluid under pressure into the circular recess of the cylindrical casing and the restricted spacing between the skirting and the cylinder to exert pressure on the O-ring and move the piston outwardly from the circular recess of the cap to expose the piston head to full air pressure to drive the piston head forwardly and the peening tool through the central bore of the shaping and ironing head.

2. The device as set forth in claim 1, characterized in that the cylindrical casing is internally provided with an annular series of spaced eccentric bores, all of which communicate with the circular recess of the cylinder casing.
